[57] CLAIM

The ornamental design for an optical disc cartridge, as shown and described.

DESCRIPTION

FIG. 1 is a top, front, and right-side perspective view of an optical disc cartridge, showing my new design; FIG. 2 is a front elevational view thereof on an enlarged scale;

FIG. 3 is a front elevational view thereof on an enlarged scale with the shutter and cartridge latch shown in the open position;

FIG. 4 is a front elevational view thereof on an enlarged scale with the cartridge latch shown in the partially open position;

FIG. 5 is a front elevational view thereof on an enlarged scale with the shutter shown in the open position and a disc inserted therein;

FIG. 6 is a rear elevational view thereof on an enlarged scale;

FIG. 7 is a rear elevational view thereof on an enlarged scale with the shutter shown in the open position;

FIG. 8 is a left-side elevational view thereof on an enlarged scale;

FIG. 9 is a right-side elevational view on an enlarged scale;

FIG. 10 is a top plan view thereof on an enlarged scale; and

FIG. 11 is a bottom plan view thereof on an enlarged scale.
